CLAIM

The ornamental design for a protective cover with an audio listening system, as shown and described.

DESCRIPTION

FIG. 1 is a top perspective view of a protective cover with an audio listening system showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed broken lines in the figures show portions of the protective cover with an audio listening system that form no part of the claimed design.

The dot-dash broken lines in the figures show boundaries that form no part of the claimed design.

1 Claim, 4 Drawing Sheets
